BAKING DISH OR SIMILAR ARTICLE

Clarence L. Maish, Warsaw, Ind.

Application October 29, 1949, Serial No. 5,772

Term of patent 14 years

(Cl. D36—2)

To all whom it may concern:

Be it known that I, Clarence L. Maish, a citizen of the United States of America and residing in the city of Warsaw, in the county of Kosciusko and State of Indiana, have invented a new and original Design for a Baking Dish or Similar Article, of which the following is the specification, reference being had to the accompanying drawings, forming a part thereof.

In the drawings:

Fig. 1 is a bottom plan view of a baking dish, showing my new design;

Fig. 2 is an end elevational view; and

Fig. 3 is a side elevational view partly in section thereof.

The ornamentation in Fig. 1 is repeated as shown completed in two of the compartments.

I claim:

The ornamental design for a baking dish or similar article, substantially as shown and described.

CLARENCE L. MAISH.
